[57] CLAIM

The ornamental design for a container lid, as shown and described.

DESCRIPTION

FIG. 1 is a perspective view of a first embodiment of a container lid showing our new design, with the broken lines

showing matter for illustrative purposes only and forming no part of the claimed design;

FIG. 2 is a front elevational view of the first embodiment of the container lid;

FIG. 3 is a rear elevational view of the first embodiment of the container lid;

FIG. 4 is a top plan view of the first embodiment of the container lid;

FIG. 5 is a right side elevational view of the first embodiment of the container lid;

FIG. 6 is a left side elevational view of the first embodiment of the container lid;

FIG. 7 is a bottom plan view of the first embodiment of the container lid;

FIG. 8 is a perspective view of a second embodiment of a container lid showing our new design, with the broken lines showing matter for illustrative purposes only and forming no part of the claimed design;

FIG. 9 is a front elevational view of the second embodiment of the container lid;

FIG. 10 is a rear elevational view of the second embodiment of the container lid;

FIG. 11 is a top plan view of the second embodiment of the container lid;

FIG. 12 is a right side elevational view of the second embodiment of the container lid;

FIG. 13 is a left side elevational view of the second embodiment of the container lid;

FIG. 14 is a bottom plan view of the second embodiment of the container lid;

FIG. 15 is a perspective view of a third embodiment of a container lid showing our new design, with the broken lines showing matter for illustrative purposes only and forming no part of the claimed design;

FIG. 16 is a front elevational view of the third embodiment of the container lid;

FIG. 17 is a rear elevational view of the third embodiment of the container lid;

FIG. 18 is a top plan view of the third embodiment of the container lid;

FIG. 19 is a right side elevational view of the third embodiment of the container lid;

FIG. 20 is a left side elevational view of the third embodiment of the container lid;

FIG. 21 is a bottom plan view of the third embodiment of the container lid;

FIG. 22 is a perspective view of a fourth embodiment of a container lid showing our new design, with the broken lines showing matter for illustrative purposes only and forming no part of the claimed design;
FIG. 23 is a front elevational view of the fourth embodiment of the container lid;
FIG. 24 is a rear elevational view of the fourth embodiment of the container lid;
FIG. 25 is a top plan view of the fourth embodiment of the container lid;

FIG. 26 is a right side elevational view of the fourth embodiment of the container lid;

FIG. 27 is a left side elevational view of the fourth embodiment of the container lid; and,

FIG. 28 is a bottom plan view of the fourth embodiment of the container lid.
